FEEDER APPARATUS FOR SPREADER STOKERS

Harold G. Meissner, Mount Vernon, and George P. Jackson, Flushing, N. Y., assignors to Combustion Engineering-Superheater, Inc., New York, N. Y., a corporation of Delaware

Application July 1, 1949, Serial No. 102,472

5 Claims. (Cl. 222—346)

1

This invention relates to apparatus for feeding fuel and other granular materials that tend to pack and it has special reference to the fuel feeder portions of spreader stokers as employed for the burning of coal and other fuel in a furnace.

An important object of this invention is to improve the design and better the performance of fuel feeders which utilize a rotating assemblage to control the advance of coal or other fuel into the spreader stoker's whirling distributor blades.

Another object is to provide a rotating feeder assemblage which is constructed and arranged so as to dislodge any fuel that adheres to surfaces with which the fuel comes into contact while advancing.

A further object is to make possible the securing of a satisfactory feed with fuel that contains a high percentage of surface moisture or for other reasons has an inherent tendency to pack.

An additional object is to improve the uniformity with which the feeder's rotating assemblage releases the fuel into the whirling distributor blades of the stoker.

Still further objects and advantages will become apparent as the description hereof proceeds.

Illustrative embodiments of our invention are disclosed by the accompanying drawings wherein:

Figure 1 is a sectional elevation through part of a spreader stoker that has the new scraper-type rotary feeder of this invention installed therein;

Figure 2 is a section on line 2—2 of Figure 1 showing one satisfactory manner in which the new feeder's rotating assemblage may be constructed and arranged;

Figure 3 is a representation in sectional elevation of our new scraper-type feeder organized somewhat differently and supplemented by a spill plate which improves the uniformity of fuel release; and

Figure 4 shows further details of the spill plate represented in Figure 3.

In the installation shown by Figure 1 fuel such as coal flows from a supply hopper 18 to a throat or passage 11 between a coal plate 12 forming a part of the feeder housing and one curved side (the left in Figure 1) of a stationary feeder cylinder 13. Feeder flights or bars 14 are advanced (counterclockwise in Figure 1) around this stationary cylinder or drum 13 to move the fuel through passage 11 and drop same from the lower edge of plate 12 between the impeller blades 16 carried by the stoker's fuel distributor shaft 17; suitable means including a plate 18 prevent fuel

2

leaving hopper 18 from reaching distributor 16—17 by way of the other side (right in Figure 1) of feeder cylinder 13. This hopper 18 is shaped and dimensioned so that even very wet coal will 5 freely advance by gravity into contact with feeder cylinder 13 without "bridging" between the walls or other parts of the hopper.

Conventional driving facilities which may include a line shaft 19 rotate the stoker's distributor shaft 17 at proper speed (such as several hundred R. P. M.) and direction (counterclockwise in the "underthrow" arrangement of Figure 1) to rapidly whirl the impeller blades 17 and thereby cause them to propel the fuel along tray 20 and discharge same through opening 21 into the furnace. The rate of such introduction of the fuel into the furnace thus is dependent upon the rate at which the fuel is delivered by the feeder 13—14 to the revolving distributor blades 16; 15 and the rate of such fuel delivery to the distributor blades may be controlled by adjusting the speed with which the feeder flights 14 are moved around cylinder 13, or by adjusting the dimensions of the throat 11 opposite the feeder 13—14 20 when the flights thereof are driven at constant speed, or by a combination of these two adjustments.

The feeder assemblage shown at 13—14 in Figures 1—2 is mounted on a shaft 24 journaled in bearings 25 that are carried by the end walls 26 of the feeder casing. One end of shaft 24 communicates with rotating means generally designated at 27 (see Figure 2); in practice these means 27 may take any one of a number of conventional forms such as mechanism (not shown in detail) driven by the stoker's line shaft 19 and serving to rotate feeder shaft 24 at a relatively slow speed (such as about five R. P. M.) that is adjustable through control lever 27' (see Figure 1). The resultant angular advancement of feeder shaft 24 either may be continuously progressive or it may proceed intermittently in step-by-step fashion; but since a continuously progressive rotation of shaft 24 is preferably in many instances it will be assumed that the driving means 27 hereof are organized to provide same.

The stationary feeder cylinder 13 derives support from shaft 24 through end hubs 29 (see Figure 2) and bearings 30 carried therein. These hubs 29 may satisfactorily be fitted into the cylinder ends and there welded in place as shown; bearings 30 may take the form of sleeve bushings treated with graphite to render them self lubricating; and closure gaskets 31 are preferably pro-

vided to seal the bearings from exposure to fuel dust which otherwise might tend to creep thereinto along shaft 24.

The feeder flights 14 earlier mentioned as riding around the outside of cylinder 13 receive support and driving motion from shaft 24 through the medium of outer hub-like cage plates 33 which are keyed to the shaft in the manner shown by Figure 2, and to the faces of which the flight ends are attached in any suitable manner as by welding. Each flight 14 terminates at a point nearly midway of cylinder 13's length and is there secured (again as by welding) to the face of an inner shroud ring 34 that encircles cylinder 13 in a manner permitting rotation relative thereto.

Each set of members 33-34 with interconnecting flights 14 thus constitutes a cage structure which rotates with the feeder shaft 24, the direction of such rotation being counterclockwise in the representation of Figure 1. This illustrative cage arrangement of Figures 1-2 utilizes four flights 14 equally spaced around the circumference of cylinder 13 and each taking the form of an L-shaped angle bar having its leading edge held either in contact with or very close to the cylinder surface in the manner shown. In moving around the curved cylinder surface each flight is thus effective to scrape same free of all adhering fuel; moreover, the angular cross section of the flights adds desired rigidity to each cage structure 33-14-34 and makes same capable of transmitting driving torque to the individual flights without causing inner shroud ring 34 to lag rotatively behind the outer hub-like cage plate 33 that is keyed to the feeder shaft 24.

Feeder flights of other cross sections and designs are of course useable at 14 and either more or less than four may be included in each cage structure. Furthermore the two cage structures embracing feeder cylinder 13 may have their flight bars 14 rotatively aligned as here shown (see left and right of Figure 2) or the flights 14 of one cage structure may be angularly displaced (as by 45°) from those of the companion structure. Only the former arrangement is represented here.

In order to restrain the feeder cylinder 13 from rotating with the cage structures 33-14-34 and the feeder's drive shaft 24, there is attached to the cylinder (as by welding) an arm 35 which projects outwardly from the cylinder surface between the inner shroud rings 34 of the two cage structures and which bears against a bracerpipe or tube 36 that spans the feeder casing as indicated in Figure 1. As shaft 24 drives feeder flights 14 around the curved surface of cylinder 13 the accompanying torque imparted to the cylinder holds restraining arm 35 against stationary pipe 36 and thus prevents the cylinder from rotating with the shaft 24 by which it is carried.

How the scraper-type feeder apparatus of Figures 1-2 operates will have become evident from the foregoing description. Coal or other fuel to be burned in the furnace is placed in hopper 10 and carried by gravity downwardly against stationary cylinder 13 and into the passage 11 thereto. While the stoker's distributor blades 16 are rapidly spun (to throw fuel supplied thereto into the furnace through opening 21), the feeder shaft 24 is rotated (as by means 27) at an appropriately slow speed and advances the feeder flights 14 around (counterclockwise in Figure 1) the curved surface of cylinder 13, the latter being held stationary by arm 35. In so advancing

through passage 11 each flight 14 moves a quantity of the fuel thereahead for droppage from the edge of plate 12 into the whirling distributor blades 16. The flow of fuel through the feeder 5 to the stoker distributor 16-17 thus is at a rate substantially proportional to the speed at which the feeder cage structures 33-14-34 are rotated by shaft 24.

A fuel feeder so organized in accordance with 10 our invention can successfully handle a wide range of fuels and offers the very practical advantage of assuring uniform feed with coal or other fuel which contains a high percentage of surface moisture. Past attempts to burn such 15 high moisture fuel with spreader stokers equipped with feeders of conventional "non-scraper" design have been accompanied by serious operating difficulties caused by: (a) coal hanging up in the stoker hopper so that the flow to the feeder 20 is either irregular or completely stopped; and (b) coal clogging the feeder with the result that it either discharges the fuel irregularly in slugs or becomes ineffective and feeds no coal. Moreover, 25 these difficulties (experienced with prior art spreader stoker feeders) became troublesome when the moisture content of the coal is increased to only about 10 or 12%.

But, the new scraper-type feeder here disclosed has been found to overcome the foregoing 30 difficulties with striking success. As earlier indicated, the fuel hopper 10 now utilized is proportioned to be "free flowing" so that even very wet coals will pass under their own weight downwardly into contact with the feeder parts 13-14 35 without hanging up in the hopper. And once having reached the new feeder assemblage even the wettest of coal can be successfully advanced therethrough at a uniform rate and without clogging. Reason for this success is that movement 40 of each feeder flight 14 around stationary cylinder 13 is accompanied by a "scraping" action which effectively frees the cylinder surface of the wet fuel particles that otherwise would adhere to the cylinder and to the flights themselves were 45 the scraping action not present.

Referring next to Figures 3 and 4, a second embodiment of our invention is there illustrated as being applied to a spreader stoker whose distributor blades 16' are spun by shaft 17' in the 50 clockwise direction to provide an "overthrow" discharge of fuel into the furnace through opening 21'. The scraper-type feeder assemblage shown in Figure 3 corresponds generally to that earlier disclosed by Figures 1-2 but differs therefrom in that the flights 14' surrounding stationary cylinder 13' take the form of bars rather than angle pieces, the cage structures including these bars are by feeder shaft 24, rotated clockwise instead of counterclockwise, the restraining arm 35' carried by the cylinder 13' bears 55 against the lower edge of a plate 38 (curved beneath the feeder cages) to resist clockwise rotation of the cylinder, and a spill plate 39 for giving more uniform release of fuel from the feeder 60 is disposed along the cylinder's discharge side (right in Figure 3) close to the circumferential edges of scraper bars 14' and in the path of fuel droppage from therebetween.

Except for the variations just indicated the 65 feeder assemblage 13'-14' of Figures 3-4 may satisfactorily duplicate the corresponding assemblage of Figures 1-2; in which event it will comprise two cage structures extending from inner shroud rings 34' (see Figure 4) through 70 flight or scraper bars 14' secured thereto and

thence to outer hub-like cage plates 33' that are keyed to feeder shaft 24' for reception of driving rotation therefrom. Said shaft 24' may be rotated by any suitable means 27A (general designation details not shown) at an appropriately slow speed which is adjustable and which provides clockwise motion as viewed in Figure 3. The resultant angular advancement of the feeder shaft and cage structures will here be assumed to be continuously progressive rather than intermittent or step-by-step. Obviously the feeder's two cage structures (left and right in Figure 4) may have been their flight bars 14' rotatively aligned as here shown or these feeder bars in one structure may be angularly displaced from those of the companion structure.

The arrangement represented in Figures 3-4 enables fuel from hopper 10' to reach whirling distributor 16'-17' only as a result of advancement downwardly around the curved right (Figure 3) side of the feeder's stationary cylinder 13': downward passage of fuel around the other (left in Figure 3) side of the cylinder being suitably blocked by fixed plate 38 and the upward motion of feeder bars 14' therealong.

Proper entrainment of a quantity of the fuel ahead of each feeder bar 14' advancing downwardly around the cylinder's right side is facilitated by equipping the top of the feeder assemblage with a cut-off plate 41 mounted to swing beneath a support shaft 42 against the torque exerted by a counterweight 43. Said torque normally holds plate 41 in the position shown but permits yielding movement thereof (towards the right) if individual lumps of fuel pushed ahead of the feeder bars 14' require same during bar passage beneath plate 41's lower edge. Effect is to level off the segments of fuel that are carried between adjacent feeder bars 14' downwardly around stationary cylinder 13' and into register with spill plate 39.

Said spill plate 39 controls the droppage of fuel from between feeder bars 14'. It may be supported in any suitable manner as by the aid of a shaft or rod 45 from which the plate hangs so as normally to lie against the circumferential edges of the feeder bars 14' that move downwardly around the cylinder's right side. Obviously supplemental means (as a spring or weight not shown) may be used to assist gravity in urging plate 39 towards cylinder 13'.

This spill plate 39 is provided with a lower or fuel-release edge (best shown in Figure 4) which is inclinedly shaped with respect to the aforesaid feeder bars 14' that pass under the plate (see Figure 3); the shaping here illustratively indicated involving a progressive downward lengthening of the plate from a high point 46 at the plate center to low points 47 at each plate side. Other equivalent inclinations of the fuel-release edge 47-46-47 may of course be employed.

In operation of the feeder apparatus of Figures 3-4, coal or other fuel to be burned in the furnace is placed in hopper 10' and carried by gravity downwardly against the stationary cylinder 13'. While the stoker's distributor blades 16' are rapidly spun (to throw fuel fed thereto into the furnace through opening 21'), the feeder shaft 24' is rotated (by means 27A) at an appropriately slow speed so as to advance the flight bars 14' around (clockwise in Figure 3) the curved surface of stationary cylinder 13'. In so moving each bar advances a quantity of

the fuel beneath cut-off plate 41 and thence downwardly into register with the spill plate 39.

Release of fuel by that spill plate from each fuel quantity between adjacent feeder bars 14' begins at the plate's center (see Figure 4) and then progressively spreads outwardly towards the plate sides as the bar 14' further moves downwardly; by the time the outer ends of one set of bars have been exposed at 47 the following set of bars thereabove have come into register with the plate's high center 46; and in this way the fuel is dropped from between the bars 14' into the stoker distributor 16'-17' at a substantially uniform rate relatively free from pulsations, assuming that feeder shaft 24' moves flight bars 14' around cylinder 13' at a substantially uniform speed.

If desired there may be placed beneath spill plate 39 above distributor 16'-17' a deflector plate 49 upon which the fuel released from the feeder drops before entering the "overthrow" whirling blades 16' of the distributor. Setting of the represented inward slope of this plate 49 for optimum effectiveness may be accomplished by moving adjustor slide 50 forward or backward beneath clamp nut 51.

From the foregoing it will be seen that we have improved the design and bettered the performance of fuel feeders which utilize a rotating assemblage to control the advance of coal or other fuel into a spreader stoker; that we have provided rotating feeder assemblages which dislodge surface-adhering fuel and enable satisfactory feeding of fuels containing a high percentage of moisture or for other reasons having an inherent tendency to pack; and that we have improved the uniformity with which the fuel is released from the feeder's rotating assemblage.

Our invention accordingly has broad utility and hence is not to be restricted to the specific forms here disclosed by way of illustration.

What we claim is:

1. In a feeder for delivering material through a passage, the combination of a rotatable shaft extending across the passage between the locations of material entry thereinto and of material discharge therefrom; a cylinder surrounding said shaft in concentric relation thereto with the cylinder's curved sides spaced from adjoining boundaries of the passage; means restraining said cylinder against rotation with the shaft, said means including a member protruding outwardly from the cylinder for engagement with a stationary stop; a cage structure mounted in concentric relation to said cylinder for rotation with said shaft and including scraper bars that extend longitudinally along the outside surface of the cylinder in spaced disposition around the cylinder's periphery, said cage structure surrounding the portion of said cylinder that is between said restraining member and one of the cylinder ends; means including said shaft for rotating said cage structure whereby to advance the scraper bars thereof around the cylinder's stationary surface and forwardly through the said space between one of the cylinder's curved sides and the adjoining passage boundary so that each bar can advance material ahead thereof through that space and in thus moving over the cylinder surface can prevent material from adhering thereto and accumulating thereon; and means preventing forward travel of material past the cylinder's other side.
2. In a feeder for delivering material through a passage, the combination of a shaft extending

across the passage between the locations of material entry thereto and of material discharge therefrom, a cylinder surrounding said shaft in concentric relation thereto with the cylinder's curved sides spaced from adjoining boundaries of the passage, means for restraining the cylinder from rotation, said means including a member protruding outwardly from said cylinder at a point intermediate its length, a first cage structure surrounding the portion of said cylinder that is between said restraining member and one of the cylinder ends and including scraper bars that extend longitudinally along the surrounded cylinder surface in spaced disposition around the cylinder's periphery, a second cage structure surrounding the portion of said cylinder that is between the restraining member and the other cylinder end and including scraper bars that extend longitudinally along the surrounded cylinder surface in spaced disposition around the cylinder's periphery, means for rotating both of said cage structures whereby to advance the scraper bars thereof around the cylinder's stationary surface and forwardly through the said space between one of the cylinder's curved sides and the adjoining passage boundary so that each bar can advance material ahead thereof through that space and in thus moving over the cylinder surface can prevent material from adhering thereto and accumulating thereon, and means preventing forward travel of material past the cylinder's other side.

3. In a feeder for delivering material such as fuel through a supply passage leading generally downwardly, the combination of a horizontally disposed shaft extending across said passage; a cylinder also spanning the passage and surrounding said shaft in concentric relation thereto with the cylinder's curved sides spaced from adjoining boundaries of the passage; means for restraining said cylinder from rotation with the shaft, said means including a member protruding outwardly from the cylinder for engagement with a stationary stop; a cage structure mounted in concentric relation to said cylinder for rotation with said shaft and surrounding the portion of said cylinder that is between said restraining member and one of the cylinder ends, said cage structure including scraper bars that extend longitudinally along the outside surface of the cylinder in spaced disposition around the cylinder's periphery and that are attached to a hub member secured to said shaft adjacent said one cylinder end; means including said shaft and hub member for imparting to said cage structure rotation which advances the scraper bars thereof around the cylinder's stationary surface and downwardly through the said space between one of the cylinder's curved sides and the adjoining passage boundary so that each bar can advance fuel ahead thereof through that space downwardly and in thus moving over the cylinder surface can prevent fuel from adhering thereto and accumulating thereon; and means preventing flow of fuel past the cylinder's other side.

4. In a feeder for delivering material such as fuel through a supply passage leading down-

wardly, the combination of a horizontally disposed cylinder extending across said passage with its curved sides spaced from adjoining boundaries of the passage and there supported against rotation, a cage structure mounted in concentric relation to said cylinder for rotation with respect thereto and including scraper bars that extend longitudinally along the outside of the cylinder in spaced disposition around the cylinder's periphery, means for imparting to said cage structure rotation which moves the scraper bars thereof around the cylinder's stationary surface so that fuel can be advanced ahead of each bar downwardly along one side of the cylinder, means preventing flow of fuel past the cylinder's other side, and a spill plate disposed along the cylinder's said one side close to the circumferential edges of said downwardly moving scraper bars and in the path of fuel droppage from therebetween, said spill plate having a lower fuel release edge inclined from parallelism with the scraper bars which pass under the plate whereby when the cage structure is rotated at a substantially uniform speed fuel will be dropped from between the scraper bars at a substantially uniform rate relatively free from pulsations.

5. In a feeder for delivering material such as fuel through a supply passage leading downwardly, the combination of a horizontally disposed cylinder extending across said passage with its curved sides spaced from adjoining boundaries of the passage and there supported against rotation, a rotatable structure including scraper bars that extend longitudinally along the outside of said cylinder in spaced disposition around the cylinder's periphery, means for imparting to said structure rotation which moves the scraper bars thereof around the cylinder's stationary surface so that fuel can be advanced ahead of each bar downwardly along one side of the cylinder, means preventing flow of fuel past the cylinder's other side, and a spill plate disposed along the cylinder's said one side close to the circumferential edges of said downwardly moving scraper bars and in the path of fuel droppage from therebetween, the lower or fuel-release edge of said spill plate being inclinedly shaped with respect to the scraper bars which pass under the plate whereby rotative advancement of those bars around the cylinder at a substantially uniform speed will cause fuel to be dropped from between the bars at a substantially uniform rate relatively free from pulsations.
